UNITED STATES PATENT OFFICE.

GEORGE H. ISLEY, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

HEATING FURNACE.

Application filed March 1, 1922. Serial No. 540,217.

To all whom it may concern:

Be it known that I, GEORGE H. ISLEY, a citizen of the United States, residing at Worcester, in the county of Worcester and 5 Commonwealth of Massachusetts, have invented a new and useful Improvement in a Heating Furnace, of which the following, together with the accompanying drawings, is a specification.

10 The present invention relates to heating furnaces of the regenerative type, wherein the air employed to support the combustion of gaseous or other fuel is subjected to a preliminary heating in advance of its admission to the furnace chamber.

15 The present invention contemplates far-reaching improvements in the way or manner of handling and heating such air, in the adaptation of the air regenerator principle 20 to a billet heating furnace; the improvements reside especially in a novel and simplified arrangement of the regenerator passages in which the air is heated, and further, in the means employed to obtain a reversal 25 of the air and combustion products through said passages. The essential features of the invention are fully set forth in the following description, reference being had to the accompanying drawings, in which—

30 Fig. 1 is a plan view, partly in horizontal section, of a billet heating furnace to which the invention is shown applied.

Fig. 2 is a longitudinal sectional view of the furnace.

35 Fig. 3 is an enlarged detail sectional view, on line 3—3, Fig. 1, of the reversing devices employed, in connection with the several passages for air and combustion products.

40 Fig. 4 is an enlarged detail sectional view, on line 4—4, Fig. 1, showing the construction employed at the point where the air is admitted.

Like reference characters refer to like parts in the different figures.

45 Referring to Figs. 1 and 2, the invention is shown applied to a heating furnace of well known type, which, for example, may be employed for the reheating of billets or the like, the latter, as shown, being conveyed 50 to the furnace longitudinally by conveyor rolls 1, 1. The billets are successively introduced broadside into the furnace through an opening 2 at one end of the same, by means of pusher devices 3 of the usual

construction. Said billets are gradually 55 moved, in a row, toward the delivery or hot end of the furnace, discharging by gravity upon a suitable incline 4 through a delivery opening 5 onto conveyor rolls 6, 6, in the manner common in apparatus of this 60 class. The admixture of gas, or other fuel, with air, and the resulting combustion of same, takes place in the furnace chamber at this delivery end, the products of combustion being withdrawn lengthwise of the furnace chamber toward the receiving end and thence discharged to the stack.

65 In all previous constructions, the preheating of the air for admixture with the gas or other fuel which enters by way of passage 7 has been accomplished by drawing or forcing said air through regenerator passages running lengthwise of the furnace,—one or the other of said passages having previously 70 been heated by the travel therethrough of the issuing combustion products, on their way to the stack. Such an arrangement of regenerators necessitates disposal of the reversing instrumentalities for the air and combustion products at one end of the furnace, well beyond the billet discharging and conveying devices and, consequently, obstructing free access to the latter and requiring a space for the furnace and its 75 appurtenances of much greater length than would be occupied in the absence of these regenerator passages. In addition, this arrangement of regenerators below and running lengthwise of the furnace, precludes 80 all possibility of access to the under side of the furnace chamber for the removal of scale and slag that accumulates therein.

85 According to the present invention, the difficulties enumerated are overcome by an arrangement of regenerator passages and reversing instrumentalities which does not increase in any way the overall length of the furnace equipment and which permits free access both to the discharge end of the furnace and to the bottom thereof. As shown 90 in Figs. 1 and 2, the air is admitted to the furnace from above, near the discharge end of the latter and adjacent to the fuel admission passage 7, substantially the same as in previous constructions, by means of a conduit or main 8. But the air is supplied to this main 8 by a pipe 9 which leads from a 95 point along one side of the furnace, rather

than from beyond the end thereof. The pipe 9, as shown in Fig. 1, communicates with an underground flue or passage 10 having, as shown in Fig. 3, two upwardly directed vertical branches 11 and 12, terminating at the ground level, on one side of the furnace. Interposed between the passages 11 and 12, and in line therewith at their terminals are a pair of passages 13 and 14, the former being in communication with a regenerator passage 15 and the latter being in communication with a regenerator passage 16.

These regenerator passages 15 and 16, of the usual checker-work construction, extend transversely of the furnace beneath the same, and one or the other of them serves for the conveyance of combustion products from the furnace to a stack passage 17, located on the opposite side of the furnace from the passages 11, 12, 13 and 14. The other of said regenerators 15 or 16 serves for the conveyance of air which is forced in in any suitable way, as by a blower 18. As shown in Fig. 4, the blower passage 19 is equipped with the usual butterfly valve 20, which, in one position, directs air into regenerator 16 and connects the regenerator 15 to the stack passage 17, and which, in the other position, directs air into the regenerator 15 and connects the regenerator 16 with the stack passage 17.

Between the terminals of the passages 13 and 14 is disposed the terminal of another passage 21, the latter connecting, by means of a flue 22, with the downwardly directed passage 23 at the end of the furnace, through which the waste products of combustion, after passing over the billets, are withdrawn. In connection with the several flue terminals 11, 12, 13, 14 and 21, is provided a reversing device consisting of a pair of shiftable hoods 24, 25, the same having depending skirts 26, 26 which are adapted to make a seal with the body of water that is contained in a base or pan 27 in surrounding relation to each of the five flue terminals 11, 12, 13, 14 and 21. Each hood 24, 25 is adapted to establish water sealed communication between two of said terminals, the hood 24 serving to connect the terminal 13 either with the terminal 11 or terminal 21, and the hood 25 serving to connect the terminal 14 either with the terminal 12 or the terminal 21,—depending upon the positions assumed by said hoods. Said hoods are constrained to move in unison, through a parallel motion, by means of pivoted links 28, 28. The right hand position of said hoods is shown in Fig. 1; the other or left hand position is shown in Fig. 3.

The terminal of each passage or flue 11, 12 is provided with a swinging cover 29, the latter being pivoted to the base 27 at 30 and 35 serving, when in lowered position, to close

and seal its respective terminal. Each cover 29 has a projection or ear 31 adapted to be engaged by the apron or skirt 26 of the adjacent hood structure. Such engagement, as shown in Fig. 3, procures the opening of the cover, and the consequent communication of its associated flue with the adjacent flue through the medium of the hood. When the hood structure is moved away from operative relation to the cover equipped flue, said cover closes by gravity and seals the end of its flue.

In the right hand position of the hood structure, as shown in Fig. 1, and with the valve 20 occupying the position shown in Fig. 4, the air for combustion, forced in by blower 18 through passage 19, is conducted by way of regenerator passage 16 and enters beneath hood 25 by way of flue terminal 14. The hood 25, in its right hand position, covers and seals the terminals 14 and 12, at the same time holding open the cover 29 of the latter terminal. As a consequence of this, the entering air, heated by its travel through the regenerator passage 16, flows downwardly through the flue 12 into underground flue 10, the left hand branch 11 of which is closed by the left hand cover 29. Hence said heated air is conveyed by pipe 9 to the conduit 8, entering the furnace adjacent to the fuel passage 7 at the end thereof where the billets are discharged. The products of combustion pass lengthwise of the furnace and down through passage 23 into flue 22, thence upwardly through flue 21 beneath the left hand hood 24. The latter connects the flue terminals 21 and 13 and hence directs the combustion products through the regenerator passage 15, the latter, as shown in Fig. 4, being connected to the stack passage 17.

To reverse the flow of air after the regenerator passage 16 has been cooled down, the hood structure is thrown over to the position shown in Fig. 3 and, at the same time, the valve 20 is moved into the dotted line position of Fig. 4. Under these conditions, the air forced in by blower 18 travels through the highly heated regenerator passage 15, and thence, by way of flue 13, hood 24 and flue 11 into the underground flue 10,—it being understood that the left hand cover 29 of flue terminal 11 is held open by hood 24, for this purpose. Under these conditions, the right hand cover 29 being closed, the heated air travels by way of pipe 9 and conduit 8 to the furnace. The products of combustion leaving by way of passage 23 and flue 22 enter the regenerator passage 16 by way of flue 21, hood 25 and flue 14, and after travelling through said regenerator passage, in order to reheat the same, leave the furnace by way of stack passage 17.

From the foregoing, it is clear that the

apparatus provides for heating the air, used to support the combustion of fuel in the furnace, in a highly efficient manner, the reversal of said air being effected in such a way that no handicap is placed on the construction of the furnace from the standpoint of introducing and delivering the metal bars or billets which constitute its product. Without increasing the space occupied lengthwise by the furnace equipment, and without sacrificing accessibility to its receiving and delivery ends, the desired regenerative action is obtained, and furthermore, no hindrance is placed in the way of removal of slag and scale from the bottom of the furnace,—the openings 32, 32 in the furnace bottom communicating with a pit 33, which affords ample space for such removal.

I claim,

20 1. The combination, with a heating furnace having uni-directional flow of combustion products therethrough, of means extending transversely thereof for regeneratively heating the air used to support combustion of fuel in said furnace.

2. The combination, with a furnace of the class described, of means for procuring the passage therethrough of combustion products in one direction only from end to end, and regenerator passages for the air supplied to said furnace, extending beneath the same from side to side.

3. The combination with a regenerative heating furnace, means for procuring the passage therethrough of combustion products in one direction only from end to end, said means comprising regenerator passages and reversing devices disposed inwardly of the ends of said furnace, whereby to give free access to said ends for the admission and removal of the material to be heated.

4. In a regenerative heating furnace having uni-directional flow of combustion products therethrough, an opening at one end for the admission of the material to be heated and an opening at the opposite end for the delivery of said material, in combination with regenerator passages and reversing instrumentalities therefor disposed wholly between said openings.

5. The combination, with a furnace of the class described, of transverse air regenerator passages and reversing instrumentalities therefor, the latter being wholly removed from the ends of said furnace, whereby to give free access to said ends for the admission and removal of material.

6. The combination, with a heating furnace having uni-directional flow of combustion products therethrough, of transverse regenerator passages for the air supplied to said furnace, and for the products of combustion therefrom, and reversing means at the terminal of said passages for reversing the direction of the currents therethrough.

7. The combination, with a heating furnace having uni-directional flow of combustion products therethrough, of regenerator passages for the air supplied to said furnace, extending transversely beneath the same, and means for reversing the passage of air and combustion products through said passages, said reversing means being disposed on opposite sides of said furnace, whereby to give free access to the ends of the furnace chamber and the ends of said passages.

8. The combination, with a heating furnace having uni-directional flow of combustion products therethrough, with an opening at one end for the admission of material to be heated, and an opening in its bottom near the other end for the removal of scale, of means interposed wholly between said openings for regeneratively heating the air used to support combustion in said furnace.

9. The combination, with a furnace of the class described, of a pair of transverse regenerator passages alternately rendered available for the admission of air, a waste gas flue from the furnace having its terminal intermediate the terminals of said regenerator passages, and reversing means, operable at said terminals, for connecting said waste gas flue to one or the other of said regenerator passages, and at the same time connecting the other regenerator passage to the air intake of the furnace.

10. The combination, with a furnace of the class described, of a pair of transverse regenerator passages alternately rendered available for the admission of air, a waste gas flue from the furnace having its terminal intermediate the terminals of said regenerator passages, an air intake to the furnace having branches coterminous with said passages and flue, and reversing means operable at said terminals for connecting said waste gas flue to one or the other of said regenerator passages, and at the same time connecting the other regenerator passage to one of said branches.

11. The combination, with a furnace of the class described, of a pair of transverse regenerator passages alternately rendered available for the admission of air, an air intake to the furnace having branches coterminous with said passages, and reversing means operable at said terminals for alternately connecting each regenerator passage with one of said branches or with the waste gas flue from the furnace.

12. The combination, with a furnace of the class described, of a pair of regenerator passages alternately rendered available for the admission of air, an air intake to the furnace having branches coterminous with said passages, a gravity acting closure for each branch, and reversing means operable at

said terminals to open one or the other of said closures, in connecting a regenerator passage terminal to its adjacent air branch terminal.

13. The combination, with a furnace of the class described, of transverse regenerators for the air and products of combustion

tion, a reversing means on one side of the furnace for said combustion products, and a second reversing means on the opposite ¹⁰ side of the furnace for the entering air.

Dated this 23rd day of February, 1922.

GEORGE H. ISLEY.
